PRINTING TELEGRAPH APPARATUS

Carl A. Levin, Chicago, Ill., assignor to Teletype Corporation, Chicago, Ill., a corporation of Delaware

Original application April 25, 1938, Serial No. 204,038. Divided and this application December 30, 1939, Serial No. 311,767

5 Claims. (Cl. 197—53)

This invention relates to printing telegraph apparatus and particularly to printing telegraph apparatus in which the characters are printed from type elements carried upon the periphery of a rotatable and selectively arrestable type wheel.

This application is a division of application, Serial No. 204,038, filed April 25, 1938 by C. A. Levin, which has matured into Patent No. 2,230,463, issued February 4, 1941.

An object of the invention resides in the provision, in a printing telegraph receiving unit embodying a type wheel having displaceable type elements, of instrumentalities for actuating said elements capable of extremely rapid positive operation.

Another object of the invention resides in the provision of a simplified easily assembled type wheel of the kind having displaceable type elements.

The invention features apparatus for actuating the individual type elements of a type wheel including a print hammer which is actuated by a cam follower and having a yieldable element included in the linkage interposed between the print cam and the print hammer whereby the actual printing operation is performed by the expenditure of kinetic energy of the print hammer and possibly an additional element or elements, such kinetic energy resulting in overtravel of the print hammer permitted by the yieldable element.

According to the present invention, a reciprocal printing member is provided for actuating the type elements individually. A bail carries a follower roller which engages the periphery of a printing cam, the bail being biased into engagement with the cam by a tension spring. Operation of the printing member is effected when the printing bail cam follower roller rides down an abrupt drop in the printing cam. The distance through which the printing bail is operated by its spring is insufficient to bring the printing member into engagement with a type element. A spring is interposed between the printing bail and the printing member, and inertia of the element to which motion is imparted by the printing bail causes that element to overtravel, the interposed spring yielding and permitting the overtravel, and the amount of overtravel is sufficient to cause a selected type element to effect printing. The spring which yields and permits the overtravel immediately retracts the printing element to unoperated position, thereby clearing

the path of unoperated type elements so that the type wheel may be rotated to a new position.

A type wheel disclosed in copending application Serial No. 77,796 filed May 4, 1936, by Albert H. Reiber and also in Patent No. 2,180,360 issued November 21, 1939, to Howard L. Krum et al. comprises spaced slotted flanges joined by a cylindrical drum portion which is also slotted. Type pallets slidable radially of the type wheel are mounted in the slots in the type wheel, there being two type pallets in each slot. The shanks of the type pallets in the upper row have recesses which open downwardly and the shanks of the type pallets in the lower row have recesses which open upwardly. A garter spring individual to each row of type pallets is disposed in the recesses in the shanks of all of the type pallets in a row and biases the pallets to their innermost positions. A floating ring partially enters the space between the two garter springs, whereby it rests upon and is supported by one of the springs and whereby it also prevents the springs from shifting out of the desired position.

In the type wheel according to the present invention, the drum portion of the wheel which joints the upper and lower flanges has a peripheral rib intermediate the upper and lower flanges. The rib thus divides the surface of the drum portion into two peripheral grooves which serve as seats for the garter springs and confine the springs in the desired position. The garter springs are thus kept in proper position without the assistance of a floating ring.

For a complete understanding of the invention, reference may be had to the following detailed description to be interpreted in the light of the accompanying drawings, wherein

Fig. 1 is a perspective view of printing telegraph apparatus including the type wheel and features of the printing mechanism in accordance with the present invention;

Fig. 2 is a plan view with portions broken away showing the overtravel printing mechanism in accordance with the present invention; and

Fig. 3 is a view partly in elevation and partly in section showing details of the type pallet operating mechanism and of the type wheel, the type pallet operating mechanism being shown in elevation and the type wheel being shown in section.

Referring now to the drawings and particularly to Fig. 1 the reference numerals 16 and 17 designate generally the typing unit and keyboard transmitter unit, respectively, of a printing telegraph apparatus embodying the present inven-

tion. The typing unit 16 is identical with that shown in Patent No. 2,247,408 issued July 1, 1941 to Albert H. Reiber and the keyboard transmitter unit 17 is identical with that shown in the said patent of Albert H. Reiber and is similar to that shown in copending application Serial No. 77,796 filed May 4, 1936, by Albert H. Reiber.

The foundation of the keyboard transmitter unit is the base casting 18, to the forward vertical wall of which is secured a slotted comb 19. A plurality of key levers 21 are pivoted within the casting 18 for rocking movement in a vertical plane and these key levers protrude from the interior of base 18 through the slots in comb 19. The key levers 21 are provided with keytops 22 and arranged to impart characteristic settings to permutation code bars contained within base 18 as fully disclosed in United States Patent No. 1,595,472 granted August 10, 1926, to Howard L. Krum. To the code bars are articulated lock levers 23 pivotally supported intermediate their ends and projecting above the upper surface of base casting 18 through apertures therein. The lock levers 23 are therefore subject to permutative setting by the code bars under the control of key levers 21.

The upwardly projecting portions of lock levers 23 cooperate individually with transmitting contact control levers 24 to determine whether or not their individual contact control levers 24 shall be permitted to operate under the control of transmitting cams 26 carried by transmitting cam assembly sleeve 27. The sleeve 27 is supported by a transmitting distributor shaft 28 to which is secured continuously driven gear 29 and to which is also secured the driving element 31 of a single revolution positive drive clutch mechanism which includes the driven element 32. A compression spring 33 urges driven element 32 to engage driving element 31 and a clutch throw-out lever 34 normally holds driven element 32 out of engagement with driving element 31. Clutch throwout lever 34 is tripped by a bell crank 36 which is operated by a lever 37 articulated to a universal bail which is contained within the base casting 18 and is operated upon the depression of any key lever 21.

The principal foundation element of the typing or receiving unit is a casting which mounts on the keyboard base 18 and has a portion 41 located centrally of the base 18 and a portion 42 extending transversely of the base in proximity to the rear edge thereof. Thumb screws are employed for securing the casting comprising portions 41 and 42 to the base 18 and one of these screws is indicated at 43. A secondary casting 44 extends transversely of the keyboard base 18 and is secured to portion 42 of the primary casting by any desired means, such as screws. The primary casting supports all of the power driven shafts, the operating cam assemblies, the selector mechanism, the printing mechanism, and the ribbon feed mechanism. The secondary casting 44 supports the platen carriage and associated mechanism, the signal bells and a set of levers by which various functions are performed.

The primary selector mechanism which integrates the signal combinations generated in the keyboard transmitter mechanism hereinbefore described, or in a remote transmitter, is indicated generally by the reference numeral 46 and is identical with the primary selector mechanism disclosed and described in considerable detail in the hereinbefore identified patent of Albert H.

Reiber No. 2,247,408. The principal elements of the selector mechanism 46 are a selector cam assembly 47, a selector magnet 48, and a sword and T lever selector assembly 49, the last mentioned assembly as well as the selector magnet being supported by a mounting plate 51 carried by the forwardly extending portion 41 of the primary casting. The selector cam assembly 47 is carried at the upper end of a vertically positioned shaft which is rotatably supported in bearing blocks 52 and 53. Friction discs are confined between end flanges of the selector cam assembly 47 and discs secured to the shaft on which the cam assembly is mounted, so that the cam assembly may rotate with the shaft or may be held against rotation. Just above the point at which it enters lower bearing block 52 the shaft has secured thereto a gear 54 which is continuously driven by an electric motor (not shown) through suitable gearing (also not shown).

The sword and T lever mechanism 49 is actuated under the joint control of selector cam assembly 47 and selector magnet 48 to interpret or integrate a series of impulses representing a signal combination preparatory to setting T levers 56 in accordance with the signal combination. Each of the T levers 56 engages one arm of a transfer bell crank 57, the other arm of which is articulated to one of the notched code discs of a code disc selector mechanism indicated generally by the reference numeral 58.

The code disc selector mechanism 58 has a circular arrangement of vertically positioned stop pins 59 which project through slots in the top-most plate of the mechanism. Stop pins 59 are biased inwardly radially of the code disc selector mechanism and near their upper ends they rest against the edges of shiftable notched code discs, as is fully disclosed in the hereinbefore identified application and patent of Albert H. Reiber, and in the patent of C. A. Levin. The notching of the code discs is such that for any permutative setting of the discs under the control of T levers 56, one and only one of the stop pins 59 finds presented to it an alignment of notches, whereupon the pin enters the alignment of notches and its upper end moves inwardly. A type wheel stop arm 61, which is clamped to type wheel shaft 62 journaled in the code disc selector 58, is of such length that in revolving it just clears those of the stop pins 59 which are held in their outermost positions by the code discs, but finds blocking its path any pin 59 which has entered an alignment of notches in the periphery of the code discs. The type wheel shaft 62 carries a gear which is continuously driven from the electric motor, and a friction clutch assembly is interposed between the gear and shaft 62 so that the shaft may remain stationary while its driving gear is rotated continuously. Shaft 62 is thus prepared to rotate at any time and is free to rotate when any stop pin 59 which had been previously selected is moved out of the path of stop arm 61 upon the resetting of the code discs. With this arrangement shaft 62 may be arrested in any angular position in which stop arm 61 encounters a stop pin 59.

The setting of the T levers 56 according to the operation of the sword lever mechanism 49 is controlled by a pivoted transfer bail 63 which is operated by a cam 68 included in a cam assembly 67 carried by a vertically extending shaft journaled in brackets 64 and 66 at the front of the printing unit. The reference numeral 69 desig-

nates a cam follower arm which is carried by the bail and by which it is operated. The shaft which carries cam assembly 67 has driving and driven clutch elements 71 and 72, the latter of which is connected to the cam assembly 67 and the former of which is connected to gear 73 which meshes with a gear 74 secured to continuously rotated gear 54. The clutch comprising elements 71 and 72 is of the single revolution positive drive type and is tripped for engagement by lever 76 under the control of receiving selector cam assembly 47.

Cam assembly 67 includes a cam 77 which is engaged by a cam follower carried by a pivoted bail 78. Bail 78 has an arm 80, the rearmost end of which is connected by a spring 79 to a type wheel supporting frame 81 which is slidable vertically upon pins 82. At the top, frame 81 has a horizontally extending portion 83 through which type wheel shaft 62 passes and in which is rotatably held the hub 84 (Fig. 3) of a type wheel 86. Hub 84 is slidable upon type wheel shaft 62 and when bail 78 is rocked in counterclockwise direction as viewed in Fig. 1 by cam 77 spring 79 causes frame 81 to move upwardly and thus type wheel 86 is lifted to bring either of two rows of type pallets into printing position. The vertically extending portion of frame 81 is provided with an arm 87 which extends into an aperture in a forwardly and rearwardly slidable member 88. The aperture in slidable member 88 is stepped to provide two stops for the arm 87 carried by frame 81. When slidable member 88 is in one position the upward movement of frame 81 is arrested by engagement of arm 87 with one of the stop surfaces when the type wheel has been elevated into position for printing from the upper row of type pallets and when the slidable member 88 is in the other position, the frame 81 is arrested when the type wheel has been elevated into position for printing from the lower row of type pallets. The movement of slidable member 88 back and forth between its two positions is controlled by the shift and unshift function mechanism of the printer as is fully disclosed in Patent No. 2,247,408 issued July 1, 1941 to Albert H. Reiber.

Printing is effected under the control of a cam 89 included in a cam assembly 91 carried by the shaft which is journaled in bearing blocks 52 and 53 and which supports the receiving selector cam assembly 47. The shaft has secured thereto the driving element 92 of a single revolution positive drive clutch mechanism and the driven element 93 of the clutch mechanism is connected to the cam assembly 91. Driven clutch element 93 is normally held out of engagement with driving element 92 by clutch throwout lever 94 which is operated once in each revolution of cam assembly 67 by cam 96 included therein.

Cam 89 is engaged on the periphery thereof by a follower roller 97 carried at the end of a print bail operating lever 98 which is pivoted at 99. Lever 98 has integral therewith an arm 101 which is provided near its outer end with a plurality of spring connection apertures 102. Any one of the apertures 102 is adapted to receive one end of a tension spring 103, the other end of which is supported by a spring post 104. Spring 103 biases lever 98 in counterclockwise direction, thus urging cam follower roller 97 into engagement with the periphery of cam 89. The several spring mounting apertures 102 in arm 101 of lever 98 are at different distances from spring post 104 so that the tension exerted by spring 103 and therefore the torque applied to lever 98 may be varied.

A print hammer operating bail 106 is pivotally supported by pivot 99 and coaxially mounted pivot 107. At its lower end bail 106 is provided with an arm 108 which supports adjustable abutment screw 109 and also one end of a tension spring 111. The inner end of abutment screw 109 engages an arm 112 of lever 98 and the rearmost end of tension spring 111 is also connected to arm 112 of lever 98. With this arrangement, bail 106 tends to occupy extreme clockwise position with respect to lever 98, the extremity of the position being determined by abutment screw 109.

Print hammer operating bail 106 has integral therewith at its upper end a lever arm 113. At its free end lever arm 113 is loosely articulated to a print hammer 114. Print hammer 114 extends between ribbon spools 116 rotatably mounted upon a ribbon feed mechanism supporting plate 117. Print hammer 114 is provided with upper and lower arms 118 and 119, respectively, which are disposed in the same vertical plane. Lower arm 119 enters a slot in a bracket 121 carried by ribbon feed mechanism foundation plate 117 and by means of slotted bracket 121 print hammer 114 is held in a vertical plane and is guided in reciprocatory motion imparted by arm 113 of bail 106. The upper arm 118 of print hammer 114 is longer than the lower arm 119 and extends across the periphery of type wheel 86 and across the upper end of type wheel shaft 62. At its free end, arm 118 is provided with a depending portion 122 which, in turn, is provided with an arm 123 the location of which is in alignment with the foremost portion of platen 124, which portion is at the level where printing occurs.

Cam 89 in its normal or rest position holds print bail operating lever 98 in extreme clockwise position in opposition to the tension of spring 103. Spring 111 holds print hammer bail 106 in extreme clockwise position with its abutment screw 109 in engagement with arm 112 of print bail operating lever 98. Thus, print hammer 114 is held in retracted position. At a predetermined time in the operation of cam 89 a sharp dropoff is presented to follower roller 97 of print bail operating lever 98. When the dropoff is encountered lever 98 is rocked sharply in counterclockwise direction by spring 103. Lever 98 imparts counterclockwise movement to bail 106 through abutment screw 109. The angular distance through which lever 98 rocks as cam follower roller 97 descends to the lowest or innermost point on the periphery of cam 89 is just short of sufficient to drive print hammer 114 positively against the type pallet aligned therewith. However, the inertia of bail 106 and print hammer 114 causes spring 111 to yield and abutment screw 109 to move out of engagement with arm 112. Thus, print hammer 114 overtravels or moves a greater distance than it would if positively interconnected with lever 98, the overtravel being caused by the inertia of bail 106 and print hammer 114 and being permitted by spring 111.

As soon as the energy generated by the inertia of bail 106 and print hammer 114 has been expended, spring 111 withdraws print hammer 114 in the direction of its retracted position until abutment screw 109 returns into engagement with arm 112 of lever 98. The remainder of the movement of print hammer 114 to its rest position is effected by the restoration of lever 98 to its extreme clockwise position by cam 89. The overtravel in the movement of print hammer 114 is sufficient to reciprocate the aligned type pallet.

radially of type wheel 86 to effect printing. During the period of overtravel and restoration, the free end of arm 118 of print hammer 114 is presented between the type pallets adjacent to that which is being operated so that the type wheel 86 could not be rotated even if permitted to do so by arm 61, due to the fact that interference between arm 123 of print hammer 114 and an adjacent unoperated type pallet would occur. Spring 111 withdraws print hammer 114 from a position of interference with unoperated type pallets much more rapidly than it could be withdrawn if positively connected to print hammer bail operating lever 98. Thus, with the arrangement hereinbefore described, the print hammer 114 is projected and retracted in the shortest possible interval of time so that more time may be allowed for the rotation of type wheel 86 to the position corresponding to the next selection.

Reference should now be had to Figs. 2 and 3 in which is shown the type pallet operating mechanism according to the present invention, which is a modification of that described with reference to Fig. 1. Reference numeral 126 designates a print hammer operating lever which is in the form of a bell crank lever and comprises arms 127 and 128. The free end of arm 127 supports a cam follower roller 129 which engages the periphery of a print controlling cam 131 which may be identical with the print controlling cam 89 in Fig. 1 and may operate in exactly the same manner and according to the same timing. The pivotal mounting for lever 126 (not shown) may be identical with pivot rod 99 of lever 98 in Fig. 1. The location of the pivotal mounting for lever 126 is indicated by the screw 132. Arm 128 of lever 126 is provided with an arcuate slot 133, the center of the arc of which coincides with the pivotal axis of lever 126. A clamping screw 134 extends through slot 133 and threadedly engages one arm 136 of a bell crank 137. Bell crank 137 is pivoted coaxially with lever 126, the screw 132 serving as the upper pivot for the bell crank. Arm 136 of bell crank 137 rests upon arm 128 of bell crank 126 and screw 134 clamps the two arms rigidly together, the slot 133 affording provision for angular adjustment of bell crank 137 relative to lever 126. Bell crank 137 has an arm 138 disposed in a horizontal plane considerably above that in which arm 136 is located and specifically in the plane of the type wheel. A vertical bar 139 integral with arms 136 and 138 interconnects the two arms and completes the bell crank 137. Upper arm 138 of bell crank 137 is provided with a plurality of apertures 141 any one of which may receive one end of a tension spring 142, the other end of which is connected to a stationary bracket 143. Spring 142 biases bell crank 137 in counterclockwise direction and thus urges cam follower roller 129 into engagement with the periphery of cam 131. Spring 142 furnishes the power for actuating the type pallets, and by shifting the foremost end of spring 142 from one to another of the holes 141, the tension of the spring may be increased or decreased as desired.

At its free end, arm 138 of bell crank 137 carries a screw 144 which supports a spring post 146. A print hammer or type pallet operating member 147 is provided in its foremost end with an open ended slot 148 which fits over screw 144, the foremost end of print hammer 147 resting upon arm 138 of bell crank 137. Print hammer 147 is guided and further supported for reciprocal movement by a bracket 149 which may

be similar to bracket 121 in Fig. 1. A tension spring 151 which has one end engaging print hammer 147 and the other end engaging spring post 146 urges print hammer 147 to extreme position of retraction which may be determined by engagement of the closed end of slot 148 with screw 144 or by engagement of a laterally extending projection 152 of print hammer 147 with adjustable eccentric 153 secured to plate 111 which supports ribbon spools 116. Print hammer 147 is provided with a shoulder 154 which may come into engagement with adjustable eccentric 153 when the print hammer is reciprocated rearwardly of the printing telegraph receiving unit to limit the operating stroke of the print hammer and prevent excessive reciprocation of the type pallets.

In Fig. 2 the printing mechanism is shown in the condition which exists just before a printing operation, bail 126 and bell crank 137 being in extreme clockwise position and the free end of print hammer 147 being retracted well back from the type pallets. As cam follower roller 129 traverses the dropoff in cam 131, lever 126 and bell crank 137 are rocked by spring 142 to extreme counterclockwise position, the movement to this position being relatively sharp. Screw 144 engages the inner or closed end of slot 148 in print hammer 147 and positively reciprocates the print hammer toward the inner end of the type pallet which is aligned therewith. The positive movement of print hammer 147 by bell crank 137 ceases when cam follower roller 129 engages the innermost portion of the periphery of cam 131 and the termination of the positive movement occurs just before the free end of print hammer 147 engages the aligned type pallet. The inertia of print hammer 147 causes the print hammer to continue to move rearwardly of the printing unit after bell crank 137 has been arrested, the inner end of slot 148 drawing away from screw 144 and spring 151 yielding to permit the additional or overtravel movement of the print hammer.

The overtravel is sufficient to drive the type pallet radially of the type wheel to effect printing, the free end of the print hammer 147 moving into the space between the type pallets on either side of the one actuated. As soon as the kinetic energy of print hammer 147 has been dissipated, spring 151 retracts the print hammer until the inner end of slot 148 engages screw 144 or until projection 152 engages eccentric 153, and such retraction is sufficient to withdraw the free end of the print hammer from between the type pallets even though the rotation of cam 131 may not have been sufficient to begin the movement of bail 126 and bell crank 137 in clockwise direction. From the foregoing it will be observed that printing is accomplished by overtravel of the print hammer as in the embodiment of the invention previously described. In the mechanism according to Fig. 2, however, only the print hammer 147 overtravels whereas in the embodiment shown in Fig. 1, the print hammer and the bell crank to which it is articulated overtravel.

Fig. 3 discloses a type wheel for the hereinbefore described printing telegraph receiving unit which may be considered as an improvement on the type wheel disclosed and claimed in Patent No. 2,180,360 issued November 21, 1939, to Howard L. Krum et al. The type wheel is indicated generally by the previously applied reference numeral 86 and its foundation is a cast or turned wheel which may comprise upper and lower flanges 161 and 162, respectively, joined by in-

tegral drum portion 163. The inner surface of drum portion 163 is cylindrical and the external drum surface includes a ridge 164 integral with the drum portion 163 and located midway between the flanges 161 and 162. The face of ridge 164 may be flat and the sides thereof are curved toward the flanges 161 and 162, the inner faces of which also curve to meet the curving sides of ridge 164 and form therewith spaced annular grooves of semicircular cross section. A plurality of radially directed type pallet slots is provided in the type wheel 86, the slots being cut entirely through the flange 162 and entirely through the drum portion 163 but only partially through the thickness of flange 161.

Each of the slots in type wheel 86 receives and slidably supports the shanks 166 of two type pallets 167. The type pallet shanks 166 extend into the interior of type wheel 86 sufficiently far that they may be engaged and actuated by print hammer 147 (Fig. 2) or 114 (Fig. 1) to effect printing. The type pallets 167 in the upper row have in their shanks 167 notches 168 which open downwardly and those in the lower row have similar notches 168 which open upwardly. A garter spring 169 extends through all of the notches 168 of the type pallets 167 in a row and biases them to their innermost positions radially of the type wheel. The annular ridge 164 which in cooperation with the inner faces of the flanges 161 and 162 defines peripheral grooves, separates the garter springs 169 and maintains them in the desired positions. When any type pallet 167 is reciprocated outwardly radially of the type wheel 86 by print hammer 147 or 114 the garter spring 169 which engages the shanks of the type pallets distends slightly, thus permitting the movement of the type pallet, and thereafter restores the type pallet to the innermost position.

The widths of the shanks of type pallets 167 are such that the lower edges of the shanks 166 of the lower row are substantially flush with the lower surface of flange 162 and the type pallets are retained in the slots in the type wheel 86 by a plate 171 which may be secured to flange 162 by a plurality of screws 172 threadedly engaging sectors of flange 162 between slots therein. Plate 171 may have a depressed central portion 173 which carries a locating pin 174 and has a plurality of apertures for clamping screws. The hub 84 slidable upon type wheel shaft 62 supports the depressed portion 173 of plate 171 and is provided with a slot 176 which receives locating pin 174 and thereby establishes a predetermined angular relation between type wheel 86 and hub 84. Clamping screws 177 extend through the apertures in the depressed portion of plate 171 and threadedly engage hub 84, thereby clamping type wheel 86 securely to the hub. Access to the screws 177 is had through the interior of wheel 86 from the top thereof.

Although specific embodiments of the features of the invention have been disclosed and described herein, it will be understood that the invention is not limited to such specific embodiments but is capable of modification, reorganization, rearrangement and substitution of parts are elements without departing from the spirit of the invention and within the scope of the appended claims.

What is claimed is:

1. In a type wheel for printing telegraph apparatus or the like, a pair of spaced flanges, a drum portion interconnecting said flanges, a

peripheral ridge integral with said drum portion disposed intermediate said flanges, said drum portion, ridge, and flanges having radially disposed slots therein, a plurality of type elements 5 arranged in rows and having shanks slidably disposed in said slots, the shanks of said type elements having notches therein, and a garter spring passing through the notches of all of the type elements in each row and biasing said type elements toward the center of said type wheel, said ridge and each adjacent flange forming a channel to maintain one of said garter springs in position in the notches of the associated row of type elements, the resiliency of each spring holding it 15 in the channel thus formed.

2. In a type wheel for printing telegraph apparatus or the like, a pair of spaced flanges, a drum portion integral with said flanges, an annular ridge integral with the drum portion on the external surface thereof, said drum portion, ridge, and flanges having slots therein radially of said type wheel, a pair of type elements having shanks slidably disposed in each of said slots, the shank of each type element in a slot having 20 a notch opening toward the shank of the other type element, and a garter spring disposed between each of the flanges and the intermediate ridge and seated therebetween, each garter spring engaging the shanks of all of the type elements 25 in a row along the edge of the notch in the shank of each type element and biasing said type elements toward the axis of said type wheel.

3. In a type wheel for printing telegraph apparatus or the like, a pair of spaced flanges, a drum portion intermediate said flanges and integral with said flanges, the inner wall of each flange being joined to the periphery of said drum portion by an arcuate surface, a ridge integral with said drum portion and carried on the periphery thereof intermediate said flanges, the side walls of said ridge being joined to the peripheral surface of said drum portion by arcuate surfaces, said flanges, drum portion, and ridge having slots extending radially of said type 35 wheel, type elements arranged around the periphery of said type wheel in rows, said type elements having shanks slidably disposed in said slots in pairs in superposed relation, the type element shanks in each slot having intercommunicating notches, and a garter spring seated upon the periphery of the drum portion between each of the flanges and the intermediate ridge, each garter spring engaging an edge of the notch in each of the type element shanks of all of the 40 type elements in a row and biasing said elements toward the axis of said type wheel.

4. In a type wheel for printing telegraph apparatus or the like, a pair of spaced flanges, a drum portion integral with said flanges and extending therebetween, said drum portion having a plurality of annular grooves in the periphery thereof, said flanges and drum portion having slots extending radially of said type wheel, type elements having shanks disposed in pairs in 45 superposed relation in each of said slots, the shanks of a pair of type elements in a slot having intercommunicating notches, and a garter spring seating in each of said annular grooves in said drum portion and engaging the edges of the notches in the shanks of all of the type elements in a row and biasing said elements toward the center of said type wheel.

5. In a type wheel for printing telegraph apparatus or the like, a drum having outwardly extending flanges, a ridge intermediate said

flanges and also extending outwardly from said drum, said flanges and ridge defining a pair of annular grooves extending around the drum, a plurality of slots formed in the drum and extending through one flange and part way through the other flange, a pair of annular rows of type pallets mounted on the drum and having shanks extending into said slots, the shanks of the type pallets of each of said rows having openings

shaped to conform in part to the contour of one of said annular grooves, and a garter spring surrounding the drum and positioned in each of said grooves and in the openings in the shanks of the type pallets of each of said rows to tend to hold the type pallets in their respective slots and to urge them radially inwardly.

CARL A. LEVIN.
